2,370,532

TRAILER TOY

John Gerlache, Chicago, Ill.

Application December 9, 1944, Serial No. 567,370

11 Claims.

(Cl. 46—107)

My invention appertains to toys of the trailer type, for example, toys wherein their traction upon a surface imparts a translation of motion to elements assembled on the body of the toy.

In this particular instance, the rotary motion of the wheels is translated to produce continuous rotary motion of two cage elements rotating in opposite directions, and located intermediately between the said two cages, a third cage structure which operates within an angular or limited radial motion reciprocating in both clockwise and counter-clockwise directions.

An important object of my invention is to provide a toy of the aforementioned character, which is operated by the traction of wheels on a surface frictionally imparting motion to cages, and cam means provided on the said toy for imparting reciprocating limited radial movement to a third cage element.

Another object of my invention is to provide a toy of the aforementioned character which is simple in construction, which will furnish amusement to those operating the toy, and which is of such simple elemental structure as to make possible economical production in quantities.

Other features, objects, and ancillary advantages resulting therefrom will become apparent from an examination of the accompanying drawings taken in conjunction with the ensuing description, wherein like numerals are utilized to designate like parts, and in which:

Fig. 1 represents a perspective view of my invention.

Fig. 2 is an end view thereof with certain portions cut away in order to more clearly depict the structure of my invention.

Fig. 3 is a top view looking down on Figure 1.

Fig. 4 is an end view as seen from the left of Figure 3.

Fig. 5 is a view similar to Figure 4, showing the other position of the cage structure when it is subjected to movement thru the traction of the wheels upon a surface.

Referring to the various figures, my invention is, generally, designated 6, and comprises a platform 7, substantially, shaped as shown, to which is secured a wire handle 8 of the shape indicated which is provided with a grip or handle portion 9. The said handle is secured to platform 7 by virtue of staples 33 which engage the bent portion 32 of the handle 8; the staples being driven into the platform 7.

Upon the platform 7 are mounted two bearing blocks 12, and below the platform are two bearing elements 14 for receiving the shaft 15,

to which are secured firmly the wheels 10 operating on the traction surface 11 and in unison with the said shaft 15. To the shaft 15, I also secure the cams 27 and 28 which have the throw 5 of the respective cams positioned in opposite segmental relationship of 180°, so that one cam is frictionally in contact, while the other cam is idle, and the situation is continually reversed, depending on the constant rotation of the wheel 10 in the same direction; the purpose of this structure will be, hereinafter, more clearly elucidated.

Within the block supports 12, I mount the shafts 13, which in turn support rotatably the cages 24 and 25 so that the bottoms 22 thereof are in frictional and gravitational contact with the traction wheels 10. The cages are, preferably, tapered in construction, and are made up of the bottom portions 22 and 21 to which the side elements or struts 23 are secured. The shafts 13 are in turn secured to an overhead support 16 to which the central shaft 34 is also secured retaining the central cage, generally, designated 26. The cages 24, 25 and 26 are rotatably operative with respect to the stationary shafts 13 and 34, and the outer cages are floatably positioned thereon, so that gravity will cause them to rest on the traction wheels, while the central cage is caused to rest alternately on the operative portions of the cams 27 and 28 depending on their position during periods of rotation of the wheels 10. The platform 7 is provided with openings 35 thru which the cams protrude to permit them to contact the base of the central cage 26.

To the bottom 18 of the central cage portion, I secure a stop 20 which may be a dowel pin suitably attached at a proper position; the said dowel pin being of sufficient length and in proper position in order to contact the bearings 12 so as to limit the motion of the central cage 26 and cause the same to move radially within the confines limited by contact with the blocks 12, alternately, during the rotation period or cycle of operation of the cams 27 and 28. The central cage portion 26 is made up of a top 17 somewhat smaller than the bottom 18, and the side slats 19 which give the cage, preferably, a tapered construction to simulate the other cages used, namely, 25 and 24.

The cams 27 and 28 are 180° out of phase, and for lending further interest to the toy, animals such as those indicated may be positioned therein, namely, a larger animal 29 in the central cage, and smaller animals 30 and 31 in cages 24 and 25 respectively.

The operation of the toy, being trailed on a surface 11 in the direction of arrow figure 1, causes the wheels 10 to rotate in the direction indicated, namely, clockwise, which in turn causes the cage 25 to rotate counter-clockwise, and the cage 24 to rotate clockwise, whereas the cage 26 is caused to rotate clockwise and counter-clockwise within the angular orbit governed by the contacting of stop 20 alternately against the bearing supports 12.

The operation of the cages is continuous in the same direction for the same directional movement, in one direction continually, when movement of the toy is caused to be propelled forward, the operation of the outer cages being synchronized to the radial and limited movement of the central cage; and conversely, when the trailer toy is pushed in the opposite direction to the arrow shown on the platform 7 in Figure 1, the reverse rotation takes place, that is, the cage 25 will be operated clockwise, cage 24 being operated counter-clockwise, whereas the same limited radial movement will be accorded to the central cage structure.

I believe, I have described and revealed rather succinctly the nature and operation of my toy invention, and inasmuch as the same is susceptible of modifications, and alterations, I hereby reserve the right to all modifications and alterations coming within the scope and spirit of my invention, also those embraced suggestively in the accompanying drawings, as well as those falling within the purview of the foregoing description.

Having thus described and revealed my invention, what I claim as novel and desire to secure by Letters Patent is:

1. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, and cam means mounted on said shaft and adapted to motivate in limited oscillatory and reciprocating movement the said second-mentioned cage means.

2. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, and cam means mounted on said shaft in contact with the base of the said intermediately positioned cage means and adapted to motivate in limited oscillatory and reciprocating movement the said second-mentioned cage means.

3. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage

means, cam means mounted on said shaft and adapted to motivate in limited oscillatory and reciprocating movement the said second-mentioned cage means, and stop means secured to the said second-mentioned cage means to govern the limited reciprocating oscillatory movement thereof.

4. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, cam means mounted on said shaft in contact with the base of the said intermediately positioned cage means and adapted to motivate in limited oscillatory and reciprocating movement the said second-mentioned cage means, and stop means secured to the second-mentioned cage means to govern the limited reciprocating oscillatory movement thereof.

5. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, cam means mounted on said shaft and adapted to motivate in limited oscillatory and reciprocating movement the said second-mentioned cage means, and an operating handle secured to the said platform.

6. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, cam means mounted on said shaft in contact with the base of the said intermediately positioned cage means and adapted to motivate in limited oscillatory and reciprocating movement the said second-mentioned cage means, and an operating handle secured to the said platform.

7. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, cam means mounted on said shaft and adapted to motivate in limited oscillatory and reciprocating movement the said second-mentioned cage means, stop means secured to the said second-mentioned cage means to govern the limited reciprocating oscillatory movement thereof, and an operating handle secured to the said platform.

8. A trailer toy comprising, a platform provided with upper bearings and lower bearings,

a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, cam means mounted on said shaft in contact with the base of the said intermediately positioned cage means and adapted to motivate in limited oscillatory and reciprocating movement the said second-mentioned cage means, stop means secured to the said second-mentioned cage means to govern the limited reciprocating oscillatory movement thereof, and an operating handle secured to the said platform.

9. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, and can means

180° out of phase mounted on said shaft and adapted to motivate in limited oscillatory and reciprocating movement the said second-mentioned cage means.

10. A trailer toy comprising, a platform provided with upper bearings and lower bearings, a shaft rotatably mounted in the said lower bearings, wheels mounted on said shaft and adapted to rotate therewith, cage means rotatably mounted in the said upper bearings, the bases thereof frictionally in contact with the rims of the said wheels, cage means rotatably mounted on the said platform and positioned intermediately the said first-mentioned cage means, and cam means 180° out of phase mounted on said shaft in contact with the base of the said intermediately positioned cage means and adapted to motivate in limited oscillatory and reciprocating movement the said second-mentioned cage means.

11. In a trailer toy, two outer cages adapted to be rotated in contra directions with respect to one another, and an intermediate cage adapted to be rotated in limited oscillatory reciprocating movement.

JOHN GERLACHE.
